CLAIM

The ornamental design for a child protective bumper for fireplace hearths and the like, as shown and described.

DESCRIPTION

FIG. 1 is a front elevation view of a child protective bumper for fireplace hearths and the like, showing my new design, it being understood that the rear is a mirror image of that shown.

FIG. 2 is a top plan view thereof, the bottom being a mirror image of that shown.

FIG. 3 is a left side elevation view thereof, the right side

being a mirror image of that shown. FIG. 4 is an enlarged fragmentary elevation view of a portion of FIG. 3.
